ICE SCRAPER

Samuel Bert, Dallas, Tex.

Application March 22, 1948, Serial No. 16,220

1 Claim. (Cl. 30—136.5)

1

This invention relates to improvements in ice scrapers or shavers, and particularly to devices of this kind embodying means for holding a receptacle, such as a cone, in position to receive the shaved ice.

One object of the invention is to provide a device of this character having novel and improved means for mounting the scraper blade and supporting and guiding the device in contact with the ice to facilitate the shaving action and to device the strain on the blade in such action.

Another object of the invention is to provide an improved construction of blade and means for mounting the same whereby the blade is firmly supported and disposed in such manner as to protect it to a material degree against liability of injury by contact with extraneous objects.

Still another object of the invention is to provide means to prevent slipping of the device from the hands of the operator.

With these and other objects in view, which will appear in the course of the subjoined description, the invention consists of the novel features of construction, combination and arrangement of parts hereinafter fully described and claimed, and as shown in the accompanying drawing, in which:

Fig. 1 is a bottom plan view of the scraper;

Fig. 2 is a view in side elevation thereof;

Fig. 3 is a vertical longitudinal section taken substantially on the line 3—3 of Fig. 1;

Fig. 4 is a vertical transverse section through the device taken substantially on the line 4—4 of Fig. 1 and showing a cone supported thereby in receiving position; and

Fig. 5 is a perspective view of the scraper blade.

In carrying my invention into practice I provide a scraper body 1 of generally cylindrical form and comprising a bottom section 2 and a top section 3. These sections are provided at the front with hinge lugs 4 and 5, connected by a pintle pin 6, whereby the sections are adapted to be opened and closed. At the rear the sections are provided with operating handles 7 and 8. One of these handles, preferably the handle 7 connected with the bottom section, is provided with a stop lug or projection 9 to prevent the hand of the operator from slipping off the handles and casually dropping the device.

The section 2 is formed to provide a scraped ice receiving chamber 10 open at top and partly closed at its bottom by a wall having sloping portions 11 and 12 converging toward its center. In the wall portion 12, adjacent the point of convergence of wall portions 11 and 12, a transverse

slot 13 is formed through which the scraped or shaved ice is admitted to the chamber 10.

Formed on the interior of the front wall portion 11 of the bottom wall is a blade supporting boss 14, having a downwardly and rearwardly inclined seat face 15, and which extends along and intersects the front wall of the slot 13. The boss 14 carries a pair of headed securing screws 16 arranged on opposite sides of its transverse center, the heads of which are equally spaced a definite distance from the seat face 15.

A cutter blade 17, having a front longitudinal cutting edge 18, is arranged to bear upon the seat face 15 and is removably held in place by the securing screws. As shown, the blade is provided with slots 19 opening through its rear or butt edge whereby it may be engaged with and disengaged from the screws when the latter are loosened and firmly fastened in position by tightening the screws. This construction provides a means whereby a dull or damaged blade may be removed for sharpening or replacement by a new blade, so that a sturdy blade adapted for long use may be employed and sharpened at intervals required.

It will be observed that the blade is so arranged in an inclined position that the major portion of the blade is enclosed within the chamber 10, and that only its cutting edge projects through and beyond the slot 13 for a cutting action, whereby when mounted in position for use the blade will be protected to a material degree from liability of injury if the scraper should be accidentally dropped or brought into contact with extraneous objects. The angle of inclination of the blade is also such that it is adapted to scrape the ice with facility and to be firmly backed by its support against the cutting strain.

In the operation of the device inclined wall portion 12 and the ridge between the wall portions 11 and 12 adapt the device to be slidably moved at different cutting angles to regulate the depth of cut, while the surface 11 permits of a sliding movement of the device away from the operator, if desired, so that the device may be reciprocated back and forth over the ice being scraped to relieve the hand of the operator of the weight of the device in both directions of movement. The depth of cut may also be varied by adjustment of the blade 17. The inclination of the surface 12 also prevents damming of the shaved ice and insures its free feed to and through the slot 13 to the chamber 10. Hence the device may be used for a large number of repeated operations with less fatigue or stoppage

due to the necessity of freeing the slot from clogged ice. The blade slots 19 are made of such length as to allow adjustment of the blade to compensate for wear and to permit of the securing of the blade in fully retracted position to prevent injury thereto in storage or shipment.

The section 3 is provided with an opening 20, which may be of flaring form or other suitable form to hold in place a cone 21 or other receptacle to be filled with the shaved ice passing thereto from the chamber 10.

From the foregoing description, taken in connection with the drawing, the construction, mode of use and advantages of my improved ice shaver or scraper will be readily understood without a further and extended description. While this construction is preferred it is to be understood that changes in the form, proportion and arrangement of the parts may be made, within the scope of the appended claim, without departing from the spirit or sacrificing any of the advantages of the invention.

Having thus described my invention, I claim:

An ice scraping and cone holding device comprising upper and lower hingedly connected cone holding and ice receiving members each of substantially circular cross section, the upper member comprising a complete ring converging upwardly and inwardly and adapted to support a cone shaped receptacle for scraped ice, and the lower member being cup-shaped and having an integral one-piece bottom portion provided with

a pair of rigid converging flat lower surfaces gently inclined upwardly and outwardly from their line of juncture, an elongated rectangular slot formed in one only of the surfaces and extending thereinto from said line of juncture, a boss formed within the bottom portion and having a flat blade supporting surface inclined generally upwardly and rearwardly from the slot, a blade housed principally within the cup-shaped member and adjustably mounted on said boss, said blade having its cutting edge extending only slightly through the slot, and a pair of unitary handles rigidly connected to said upper and lower members respectively and serving as operating means to draw the blade across a cake of ice while the device is supported and guided in contact with the ice by said rigid flat converging lower surfaces of the ice receiving member.

SAMUEL BERT.
